Patented Aug. 6, 1918.

UNITED STATES PATENT OFFICE.

MARK SHOELD, OF CHICAGO, ILLINOIS, ASSIGNOR TO ARMOUR FERTILIZER WORKS, OF CHICAGO, ILLINOIS, A CORPORATION OF NEW JERSEY.

ELECTRIC FURNACE.

1,274,794.

Specification of Letters Patent.

Patented Aug. 6, 1918.

Application filed January 28, 1918. Serial No. 214,053.

To all whom it may concern:

Be it known that I, MARK SHOELD, a subject of the King of Sweden, residing at Chicago, in the county of Cook and State 5 of Illinois, have invented certain new and useful Improvements in Electric Furnaces, of which the following is a specification.

My invention concerns electric furnaces and the production of desired chemical 10 actions thereby. While the invention has many broad features of novelty, it is of especial use in, but not necessarily limited to, the production of aluminum nitrid which requires a high degree of heat to effect the 15 required chemical result.

One object of the invention is the provision of a furnace of this type which will produce a substantially-uniform heat throughout a certain zone or section of the 20 material treated and in which the electrodes will not be consumed either electrically or chemically. A further feature of the new furnace is the assurance that the gas used will be uniformly dispersed or distributed 25 through the pieces of particles of solid material treated. Another purpose of the invention is to so arrange the travel of the solid and gaseous materials that they will tend to confine the heat to a certain limited 30 desirable zone; the gas being preliminarily heated by the hot solid material, and the solid material being initially heated by the hot escaping gas. A further purpose of the invention is the use of a lining for the 35 furnace capable of withstanding the high temperatures necessary for an indefinite period without deterioration and protecting such lining in various ways to prevent its undue wear or impairment. Still another 40 object is to so construct the furnace and use the material treated that the latter shall prevent electric short circuiting.

In order that those skilled in this art may have a full and complete understanding of 45 this invention and its various structural and functional advantages, I have illustrated a preferred embodiment of the same in the accompanying drawing throughout the

views of which like reference characters refer to the same parts, and to which drawing reference should be had in connection with the following detailed description. 50

In the drawing:

Figure 1 is a vertical section through the furnace, and 55

Fig. 2 is a horizontal section on line 2—2 of Fig. 1.

The furnace comprises a structure with a central vertical passage or chamber 10 octagonal in cross-section (Fig. 2), although its particular shape is immaterial so long as it is positioned substantially vertically to secure a corresponding feed of the material by gravity. Such passage or compartment at its central portion is lined with carbon 60 bricks or blocks 11, 11, surrounding which is a ring 12 of black-bricks of special composition, and outside of these are fire-bricks 12 which also form the upper flared portion 14 of the passage and a lower portion 15 70 thereof. Outside of such fire-bricks is a layer or stratum of silocel bricks 16, and around this is an exterior metal shell or casing 17 which also covers the top and bottom of the furnace, the whole being supported on concrete pillars or posts 18, 18. 75

At its top, this outwardly-widening or flaring chamber divides into two diverging branches 19 and 20 through which the material to be treated is introduced into the furnace, such material being ordinarily in the form of briquets, composed of finely-divided alumina and carbon held together with a suitable binder. Each such branch has an upstanding gas outlet 21 and a poke 85 hole 22.

Disposed centrally in passage 10 is an upright, graphite electrode 23 extending upwardly through the metal housing and exteriorly of the furnace associated with a 90 water-jacketed electrode-clamp 24, to which an electric conductor 25 of a suitable electric circuit is fastened.

The companion electrode of the circuit comprises an encircling graphite ring 26 located substantially in the middle of the 95

furnace with portions of the carbon-lining both above and below it, and composed of a series of graphite-blocks wedged together into adequate physical and electrical contact. Such ring is connected to the electric circuit referred to by means of two, opposite, spaced, graphite conductors 27 and 28 maintained in adequate contact with the ring and each supplied outside of the furnace with a clamp 29, cooled by a spray 30, fastened to an electric wire or cable 31. Where these electrodes 27 and 28 pass through the metal-shell and also around the clamp 24, I provide a suitable supply of asbestos cement 32 as a sealing means.

In its lower portion, the furnace has a tube or conduit 33 directly connected to and beneath the main passage to the furnace through which pure nitrogen, or impure nitrogen containing a small percentage of carbon monoxide, is introduced into the furnace under pressure.

To assist in cooling the furnace, the fire-bricks of its upper part may have embedded in them a cooling water-coil 33.

In the operation of the improved appliance the briquets referred to are introduced continuously or substantially continuously into the two branch passages 19 and 20 and the product is continuously removed from the bottom of the furnace, both without permitting an escape of the gas. It has been deemed unnecessary to illustrate these details as they are well known and may be of any suitable construction.

In carrying out the process by this particular apparatus, it may be remarked that the briquetted solid material or mixture will not, when cold, permit a passage of electric current of appreciable volume between the center electrode and its companion ring electrode. In other words, the current will not be initiated or established. It is, therefore, necessary to prime the apparatus by using graphite to start the current flowing. Such current then, during the constant gradual descent of the briquets, in passing through such material from the one electrode to the other substantially-uniformly heats the material by reason of the resistance which it offers to the passage of the current flow. Such heating, however, is limited to the region of the electrodes because of the greater resistance of the carbon and the sufficiently great resistance of the relatively-cool incoming or downflowing briquets. Nor does such electric current in its heating effect travel downwardly even though some of the carbon lining and the solid material being treated are below the ring contact. This is due to the fact that the relatively-cool ascending column of gas keeps the temperature of the briquets sufficiently low, that is to say, keeps

the resistance of the material high enough, to prevent the current from passing at this point.

Inasmuch as the descending column of material travels downwardly in a vertical path and the gas passage is vertical, such gas distributes itself uniformly through the evenly heated briquets at the plane of the electrodes, thus bringing about a thorough and complete chemical reaction. The descending incoming body of cool material and the ascending incoming body of cool gas, both tend to confine the heated current-carrying zone to the plane or place of the electrodes, thus desirably centrally confining the heat. Inasmuch as the inner electrode is entirely surrounded by the briquets, the latter prevent short circuiting between the electrodes and there is complete assurance that the current will pass equally throughout such material and heat it practically uniformly.

It will be easily understood that the outer ring electrode is adequately supported and not subject to damage or injury, and that since the center electrode is arranged or disposed vertically it is freed from strains which might otherwise tend toward its injury. Furthermore, since no electric arc is employed, there is no electrical consumption of the electrodes, and since the gas employed has no oxidizing effect there is no chemical deterioration of the electrodes. Furthermore, a slight excess of carbon is used in the briquets so that this may be considered as a safety measure with respect to undesirable chemical effects on the carbon lining.

While I have herein presented one preferred and desirable embodiment of the invention, it is to be understood that the latter is susceptible of a variety of embodiments and that many minor mechanical changes may be incorporated in the structure presented without departure from the substance and essence of the invention and without the sacrifice of any of its substantial benefits and advantages.

I claim:

1. In an electric-furnace of the character described, the combination of a furnace-body, an electrically-conductive lining for the heat-chamber thereof, electrodes of electrical conductivity greater than that of said lining arranged to contact with the contents of said heat-chamber and direct a current of electricity therethrough, said contents completing the electric circuit between said electrodes, and means to cause the material to be treated to pass between said electrodes, substantially as described.

2. In an electric-furnace of the character described, the combination of a furnace-

body, a carbon-lining for the heat-chamber thereof, electrodes of electrical conductivity greater than that of said carbon-lining arranged to contact with the contents of said 5 heat-chamber and direct a current of electricity therethrough, such contents completing the electric circuit between said electrodes, and means to cause the material to be treated to pass between said electrodes, 10 substantially as described.

3. In an electric-furnace of the character described, the combination of a furnace-body, a carbon-lining for the heat-chamber thereof, graphite electrodes of electrical conductivity greater than that of said carbon-lining 15 arranged to contact with the contents of said heat-chamber and direct a current of electricity therethrough, such contents completing the electric-circuit between said 20 electrodes, and means to cause the material to be treated to pass between said electrodes, substantially as described.

4. In an electric-furnace of the character described, the combination of a furnace-body, an electrically-conductive lining therefor, and electrodes arranged to send a current of electricity through an intermediate portion only of the contents of said lining and of electrical conductivity greater than 30 that of said electrically-conductive lining, substantially as described.

5. In an electric-furnace of the character described, the combination of a furnace-body having a vertical passage therethrough, an 35 outer substantially-horizontal ring electrode disposed exteriorly of and adapted to contact with the material to be treated in said furnace body, a center electrode supported from above and projecting down into the 40 plane of said ring electrode, means to feed the material to be treated downwardly between said electrodes, and means to send a current of gas through the material between said electrodes, whereby said interposed material may be heated by an electric current 45 between the electrodes and be subjected simultaneously to the action of the gas, substantially as described.

6. In an electric-furnace of the character 50 described, the combination of a furnace-body having a vertical passage therethrough, an outer substantially-horizontal ring electrode disposed exteriorly of and adapted to contact with the material to be treated in said 55 furnace-body, a center electrode supported from above and projecting down into the plane of said ring electrode, means to feed the material to be treated downwardly between said electrodes, and means to send a 60 current of gas upwardly through the material between said electrodes, whereby said interposed material may be heated by an electric current between the electrodes and

be subjected simultaneously to the action of the gas, substantially as described. 65

7. In an electric furnace of the character described, the combination of a furnace body having a vertical passage therethrough, a carbon-lining for said passage, a vertically-disposed graphite electrode extending into 70 the cavity of said body and adapted to be surrounded by and in contact with the material to be treated, an outer graphite-ring electrode disposed exteriorly of and adapted to contact with the material to be treated, 75 and means to send a current of gas upwardly through said passage and the material interposed between said electrodes, whereby said material may be simultaneously subjected to the action of the gas and to a heating current of electricity through said electrodes, 80 substantially as described.

8. In an electric-furnace of the character described, the combination of a furnace-body having a vertical passage therethrough, 85 an electrically-conductive lining for said passage, a vertically-disposed electrode extending into the cavity of said body and adapted to be surrounded by and in contact with the material to be treated, an outer ring electrode disposed exteriorly of and adapted to contact with the material to be treated, and means to send a current of gas upwardly through said passage and the material interposed between the electrodes, 90 whereby the material may be simultaneously subjected to the action of the gas and to a heating current of electricity through said electrodes, 95 said electrodes being of greater electrical conductivity than said lining, substantially as described. 100

9. In an electric furnace of the character described, the combination of a furnace body having a vertical passage therethrough, a carbon-lining for said passage, a vertically-disposed graphite electrode extending into 105 the cavity of said body and adapted to be surrounded by and contact with the material to be treated, an outer graphite ring electrode disposed exteriorly of and adapted to contact with an intermediate section only of the material to be treated, and means to send a current of gas upwardly through said passage and the material interposed between said electrodes, whereby said material may be simultaneously subjected to the action of the gas and to a heating current of electricity 115 through said electrodes, substantially as described.

10. In an electric-furnace of the character described, the combination of a furnace-body having a vertical passage therethrough, an electrically-conductive lining for said passage, a vertically-disposed electrode extending into 120 the cavity of said body and adapted to be surrounded by and contact with the

material to be treated, an outer ring electrode disposed exteriorly of and adapted to contact with an intermediate section only of the material to be treated, and means to send 5 a current of gas upwardly through said passage and the material interposed between said electrodes, whereby said material may

be simultaneously subjected to the action of the gas and to a heating current of electricity through said electrodes, said electrodes 10 being of greater electrical conductivity than said lining, substantially as described.

MARK SHOELD.
